E. B. LEAR

VALVE FOR ROCK DRILLS

Filed April 7, 1927

FIG. 1.

FIG. 2.

INVENTOR.
Earl B. Lear.
BY *Robert B. Ogden*
HIS ATTORNEY.

UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

VALVE FOR ROCK DRILLS.

Application filed April 7, 1927. Serial No. 181,730.

This invention relates to rock drills, but more particularly to a distributing valve for fluid actuated rock drills of the hammer type.

- 5 The objects of the invention are to obtain a light-weight valve capable of rapid reciprocation, to simplify the construction and reduce the cost of manufacturing valves of this type.
- 10 Other objects will appear hereinafter, and to all of these ends the invention consists of the combination of elements, features of construction and arrangement of parts substantially as hereinafter described and claimed.
- 15 and illustrated in the accompanying drawings, in which

Figure 1 is a longitudinal sectional elevation of a portion of a rock drill showing the valve in position for admitting pressure fluid into the rearward end of the cylinder, and

20 Figure 2 is a view similar to Figure 1 showing the valve in position for admitting pressure fluid into the front end of the cylinder.

25 Referring to the drawings, the invention is shown embodied in a rock drill having a cylinder A in which is disposed a reciprocating hammer piston B. The piston B has a forwardly extending nose C cooperating slidably with a front cylinder washer D which forms a closure for the front end of the cylinder A. A closure is provided for the rearward end of the cylinder A in the form of a back head E in which is disposed a throttle valve F for controlling the admission of pressure fluid from a source of supply (not shown) to a passage G in the back head E.

30 On one side of the cylinder A and preferably extending longitudinally thereof as illustrated, is a valve chest H having an annular recess J which extends from the rearward end of the valve chest H to a point

35 near the front end thereof, thus forming a wall K at the front end of the valve chest H.

The open end of the recess J is in this instance enlarged as at L to receive a flange O of a valve bushing P disposed in the recess J.

In this way the bushing P is held against 50 movement in a forwardly direction and by forming the end of the bushing P flush with the rearward end of the valve chest H, said bushing may also be held against movement in a rearwardly direction by the back head 55 E which extends across the rearward end of the valve chest.

Any suitable means, such as the usual side bolts (not shown), may be provided for clamping the back head E securely to the 60 cylinder A.

As will be observed, the inner end of the bushing P terminates at a point adjacent an exhaust port Q in the valve chest H. On the opposite side of the exhaust port Q is 65 disposed another bushing R which abuts with its front end the wall K. The bushings P and R have bores S and T respectively, and at the inner or adjacent ends of these bores are formed enlarged recesses U which, 70 together with the bores S and T, form a valve chamber V for a distributing valve W.

The distributing valve W is of the hollow type, that is, it has a longitudinal bore X which extends throughout the length of the 75 valve and the ends of the bore X in this instance cooperate slidably with plugs Y and Z. The plug Y extends through the bushing P whereby it is also supported and has a passage b which registers with the passage 80 G for admitting pressure fluid into the bore X of the valve.

In this instance pressure fluid is conveyed intermittently through ports Y' from the interior of the plug Y to the rearward end 85 of the valve chamber V to act against the rearward end of the valve for holding the valve firmly in its extreme forwardmost position. In order to enable the escape of pressure fluid thus utilized for holding the valve, 90 the valve chest H and the bushing P are provided with a vent c leading to the atmosphere.

The plug Z comprises a body portion d 95 which extends into the front end of the valve W and has a reduced threaded extension e which projects through the wall K to receive a nut f whereby the plug Z may be drawn

firmly against the bushing R and the bushing R firmly against the wall K. The plug Z also serves to convey pressure fluid to the front end of the valve chamber V for holding the valve temporarily in its rearwardmost position. To this end the said plug is provided with a passage *g* from which radiate passages *h* for conveying pressure fluid to the front end of the valve chamber. At this 10 end of the valve chamber is also formed a vent *c* for exhausting the pressure fluid utilized for holding the valve rearwardly.

Preferably near the rearward end of the valve W are formed ports *j* which, when the 15 valve is in its forwardmost position or when the valve is approaching this position, will register with an inlet passage *k* leading from the valve chamber V to the rearward end of the cylinder A. The front end of the valve 20 is likewise provided with similar ports *o* adapted to register with a front inlet passage *p* leading from the valve chamber V to the front end of the cylinder A. The ports *j* and *o* are preferably so positioned that 25 when they are moved out of communication with respect to the inlet passages wherewith they are intended to register they will also be covered by the ends of the plugs extending into the valve. In this way is formed a 30 double seal for preventing leakage of pressure fluid from the interior of the valve into the cylinder.

Intermediate the ends of the valve W is 35 formed an enlarged flange *q* which cooperates slidably with the recesses U and has rearward and forward actuating surfaces *r* and *s* respectively against which pressure fluid may act for actuating the valve from one extreme position to the other. Such 40 pressure fluid in this instance is conveyed from the cylinder to the rearward recess U through a kicker passage *t* crossed with respect to a kicker passage *u* leading from the cylinder at a point rearwardly of a free exhaust port *v* to the forward recess U. The 45 kicker passage *u* conveys pressure fluid from the cylinder to act against the front actuating surface *s* for throwing the valve rearwardly. Both the kicker passages *u* and *t*, 50 as well as the free exhaust port *v*, are in this instance controlled by the piston B.

The operation of the device is as follows: 55 With the valve and piston in the positions shown in Figure 1 pressure fluid entering the bore X of the valve will pass through the ports *j* and the inlet passage *k* to the rearward end of the cylinder to move the piston B forwardly. The valve will remain in this position until the kicker passage *u* is un- 60 covered by the piston, whereupon pressure fluid will flow into the front recess U and, acting against the actuating surface *s*, will move the valve rearwardly to the position shown in Figure 2. However, while the 65 valve is in its forwardmost position, the

ports Y' are also uncovered by the valve, so that pressure fluid may flow into the valve chamber to act against the rearward end of the valve for holding the valve immovably in its extreme forwardmost position. Obviously the pressure fluid acting against the rearward end of the valve will be somewhat lower than line pressure as this end of the valve is constantly open to atmosphere. This, however, will result only in a reduction in pressure as the vent *c* is of such cross sectional area that there will be a sufficient pressure acting against the valve to hold it against trembling.

Assuming now that the valve is in the 80 position illustrated in Figure 2, pressure fluid will flow through the ports *o*, the inlet passage *p* into the front end of the cylinder to return the piston. In this position of the valve the ports Y' will be covered by the 85 rearward end of the valve and the ports *h* in the plug Z will be uncovered by the front end of the valve to admit pressure fluid into the front end of the valve chamber holding the valve V in its rearwardmost position. Upon the admission of pressure fluid into the recess U of the bushing P the valve W will again be actuated forwardly, thus completing the cycle of operations.

As will be observed, the flange *q* in addition to providing actuating surfaces for throwing the valve also controls the exhaust port Q and after the valve has been actuated a sufficient distance to uncover the ports Y' or *h*, as the case may be, the pressure fluid utilized for throwing the valve will be immediately exhausted to the atmosphere through the exhaust port Q.

I claim:

1. In a fluid actuated rock drill, the combination of a cylinder and piston, a valve chest having a valve chamber, inlet passages leading from the valve chamber to the ends of the cylinder, a hollow valve in the valve chamber constantly exposed interiorly to live pressure fluid, said valve having ports to register with the inlet passages, a flange on the valve intermittently exposed at its ends to live pressure fluid from the cylinder for actuating the valve, recessed plugs cooperating slidably with the valve, and passages in the plugs admitting pressure fluid into the ends of the valve chamber for holding the valve during the admission of pressure fluid to the cylinder, said passages being controlled by the valve.

2. In a fluid actuated rock drill, the combination of a cylinder and piston, a valve chest having a valve chamber, inlet passages leading from the valve chamber to the ends of the cylinder, a hollow valve in the valve chamber constantly exposed interiorly to live pressure fluid, said valve having ports to register with the inlet passages, a flange on the valve intermittently exposed at its ends

to live pressure fluid from the cylinder for actuating the valve, plugs cooperating slidably with the valve, passages in the plugs admitting pressure fluid into the ends of the valve chamber for holding the valve during the admission of pressure fluid to the cylinder, and vents leading from the ends of the

valve chamber to the atmosphere for exhausting the pressure fluid utilized for holding the valve.

In testimony whereof I have signed this specification.

10

EARL B. LEAR.
